UNITED STATES PATENT OFFICE.

WHEELER H. VIBBER, OF NEW LONDON, CONNECTICUT, ASSIGNOR TO THE GILLETTE-VIBBER CO., OF NEW LONDON, CONNECTICUT, A CORPORATION.

CONDUIT-CAP FOR ELECTRIC INSTALLATION.

No. 897,683.

Specification of Letters Patent.

Patented Sept. 1, 1908.

Application filed February 6, 1908. Serial No. 414,582.

To all whom it may concern:

Be it known that I, WHEELER H. VIBBER, a citizen of the United States, residing at New London, in the county of New London 5 and State of Connecticut, have invented a new and useful Improvement in Conduit-Caps for Electric Installation; and I do hereby declare the following, when taken in connection with the accompanying drawings 10 and the letters of reference marked thereon, to be a full, clear, and exact description of the same, and which said drawings constitute part of this specification, and represent, in—

Figure 1 a view in side elevation of my improved conduit cap as converted for capping a horizontal electric conduit. Fig. 2 a view thereof in rear elevation with a portion of the cover broken away. Fig. 3 a plan view thereof with the cover removed. Fig. 4 a view in vertical central section on the line *a—b* of Fig. 2. Fig. 5 a plan view on a reduced scale of the frame or body as it appears when stripped. Fig. 6 a detached view partly in plan and partly in section of the 25 outer half of the insulator. Fig. 7 a view thereof in inside elevation.

My invention relates to an improved conduit cap forming an end-terminal for electric installation, the object being to produce a 30 simple, compact and convenient cap constructed with particular reference to conversion for use upon either vertical or horizontal conduits or pipes and to being provided with a porcelain insulator.

With these ends in view my invention consists in the construction and combination of parts to be hereinafter described and pointed out in the claims.

In carrying out my invention as herein shown, I employ a frame or body comprising, as it may be said, a horizontal wall or bottom 2 and a vertical wall or side 3 meeting at a right angle and curved at their ends when viewed in plan. In default of a better term, 45 the frame might be described as scoop-like. The said horizontal wall 2 is formed midway of its length with a tapered circular opening 4 larger at its outer than at its inner end, while the vertical wall 3 is provided midway 50 of its length with an opening 5 exactly corresponding in form and diameter to the said opening 4, the said walls being thickened where these openings are formed by the formation of a boss 2^a upon the inner face of the 55 wall 2 and of a boss 3^a upon the outer face of

the wall 3. These openings 4 and 5 which are located close together, are adapted to receive a tapered plug 6 formed with a central threaded hole 7 for the reception of a screw 8 which passes through a bridge 9 longer than 60 the diameter of the openings and designed to bridge either one opening or the other according to the opening that is to be closed by the plug 6.

If the cap is to be used for the purpose of 65 capping a vertically arranged conduit or pipe, the plug 6 is located in the opening 4. By shifting the plug from one opening to the other the device may be readily converted for use in capping a vertical or horizontal 70 conduit or pipe as may be required, the operation of converting the cap for one use or the other being very easily effected, and the cap when converted being virtually the same as though it were originally designed for one 75 use only. As shown, the cap is converted for use with a horizontal conduit or pipe. The plug 6 is therefore located in the opening 4, leaving the opening 5 free for the introduction into it of a thimble-like coupling which 80 is introduced into it from the inside of the frame, passing thence outward. This thimble-like coupling comprises two differentiated ends 10 and 11 and is formed at its inner end with a flaring flange 12 larger in diameter than the inner ends of the openings 4 and 5. The said thimble-like coupling is also provided at a point midway between its 85 ends with an externally threaded shoulder 13 for the application of a binding nut 14 by 90 means of which it is drawn outward and its flaring flange 12 seated against the inner edges of the walls of the said openings, the flaring form of the flange 12 making it self-adjusting. The outer portion of the coupling 95 is formed with internal threads 15 for the reception of the threaded end of the pipe or conduit capped. The exterior surface of the outer end of the coupling, beyond the threaded shoulder 13, being unthreaded, provides for the application of a wrench. As 100 shown, the conduit capped is the horizontal conduit 16.

The horizontal wall or bottom 2 of the 105 scoop-shaped frame or body of the device, is formed at its ends with two parallel corresponding arms 17 separated by a space 18 which receives a porcelain insulator composed of two corresponding parts 19 and 20 110 the ends of which are formed with register-

ing grooves 21 which receive the arms 17. The inner member 19 is formed with a longitudinal groove 22 receiving, as shown, the upturned edge of the wall 2 while the outer member 20 is formed with a corresponding longitudinal groove 23 which makes the insulator reversible edge for edge, fitting into place as well when presented one way as the other. The members 19 and 20 are formed 5 in their inner edges with semicircular transverse grooves 24, 25 and 26 which, when brought into registration, form round holes for the passage of the wires or cables into the interior chamber 27 of the cap. For the purpose of closing in any of these holes that may 10 not be in use, the said grooves 24, 25 and 26 are formed with secondary seal-receiving grooves 28 for the reception of small disk-like seals which may be of any approved material, and if desired, cemented in place. Of course the number of holes in any insulator may be varied according to circumstances. By making the insulator in two parts I avoid the necessity of drawing the wires or cables 15 through it which is inconvenient, time-consuming and objectionable. In the use of my device, the outer part of the insulator is removed and the wires or cables adjusted with respect to the inner part after which the 20 outer part is restored to place.

The chamber 27 is inclosed by a dome-like cover 29 held in place by screws 30 entering the opposite ends of the vertical wall 3 the upper corners of which are cut away, the cover 25 being formed with a large open slot 31 which fits over the boss 3^a upon the outer face of the vertical wall 3.

To permit the escape of any moisture that may work into the joint 32^a between the edge 40 of the boss 3^a and the wall of the slot 31, I form two vertical grooves 32 in the wall 3.

I claim:—

1. In a convertible cap forming an end-terminal for electric conduits, the combination 45 with a body having a vertical and a horizontal wall merging into each other at a right angle, and each formed with an opening, the said openings being located close together; of a plug adapted to be introduced into one 50 opening or the other according as it is desired to use the device for capping a horizontal or vertical conduit.

2. In a convertible cap for electric conduits, the combination with a body having a 55 vertical and a horizontal wall, each formed with a tapered opening, of a tapered plug adapted to fit into either one of the said openings and formed with a central threaded hole, and a bridge and a screw for drawing the plug 60 into place in one of the said openings and holding it therein, the plug being located in either one opening or the other according as the cap is to be used for capping a vertical or horizontal conduit.

3. In a cap for electric conduits, the combi-

nation with a body formed with an opening, of a thimble-like coupling having its inner end flared to form a self-adjusting flange co-acting with the inner edge of the wall of the said opening, and the said thimble having its outer end threaded and formed between its ends with an externally threaded shoulder; and a nut applicable to the said shoulder for drawing the thimble into place in the opening. 70

4. In a convertible cap for electric conduits, the combination with a body having a horizontal and a vertical wall each formed with an opening, of a plug for closing one opening like the other, and a thimble or coupling for introduction into the opening not occupied by the plug. 75

5. In a cap forming an end-terminal for electric conduits, the combination with a body provided at its ends with arms separated by a space, of a cover fitting over the said body to form a chamber, and an insulator located in the said space and having its ends grooved for engagement with the said arms and its sides grooved for engagement 85 with the edge of the portion of the body lying between the said arms. 90

6. In a cap for electric conduits, the combination with a body provided at its ends with arms separated by a space, of a cover 95 fitting over the said body to form a chamber, and an insulator located in the said space and having its ends grooved for engagement with the said arms, whereby the insulator is supported. 100

7. In a convertible cap forming an end-terminal for electric conduits, the combination with a body having a vertical and a horizontal wall merging into each other at a right angle and each formed with an opening, and the said openings being located close together; of a plug adapted to be introduced into one opening or the other according as it is desired to use the device for capping a horizontal or a vertical conduit, a cover fitting over 110 the said body to form a chamber, and a two-part insulator mounted in the lower wall of the said body and located at the entrance into the said chamber. 115

8. An insulator for electric conduits, made in two parts each formed with transverse grooves which, when registered, form holes for the passage of electric wires, and the said grooves being formed with secondary seal-receiving grooves, in combination with disk-like seals entered into the said secondary grooves for closing the said holes when the same are not required for use and with means for holding the said two parts of the insulator together. 120

9. A two-part insulator having its respective parts formed at their ends and sides with grooves by means of which it is supported in place, and the said parts being formed upon their inner faces with semi-circular grooves 125 130

which register to form holes for electric wires, and the said grooves being formed with secondary seal-receiving grooves; in combination with disk-like seals entered into the said 5 secondary grooves for closing the said holes when the same are not required for use and with means for holding the said two parts of the insulator together.

10. In a convertible cap for capping electric conduits, the combination with a body having a vertical and a horizontal wall each formed with an opening and the vertical wall being formed upon its outer face with a boss

in which the opening in the vertical wall is formed; of a plug adapted to be located in 15 one of the said openings, an insulator carried by the said body, and a cover fitting over the said body and formed with a slot to fit over the said boss.

In testimony whereof, I have signed this 20 specification in the presence of two subscribing witnesses.

WHEELER H. VIBBER.
